(57) **CLAIM**

The ornamental design for a bearer, as shown and described.

DESCRIPTION

FIG. 1 is a front, top and right side perspective view of a BEARER showing our new design;

FIG. 2 is an enlarged front view thereof, the rear view being symmetrical to the front view;

FIG. 3 is a top plan view thereof;

FIG. 4 is a bottom plan view thereof;

FIG. 5 is a right side view thereof;

FIG. 6 is a left side view thereof;

FIG. 7 is an enlarged cross-sectional view taken along line 7-7 in FIG. 3; and,

FIG. 8 is an exploded perspective view thereof.

The broken lines illustrate portions of the bearer that form no part of the claimed design. The dash-dotted lines denote the boundary of the claim and form no part of the claimed design.
